United States Patent Office.

JOHN COOPER, OF DUBLIN, INDIANA.

Letters Patent No. 75,629, dated March 17, 1868; antedated March 6, 1868.

IMPROVED WASHING-MACHINE.

The Schedule referred to in these Letters Patent and making part of the same.

TO ALL WHOM IT MAY CONCERN:

Be it known that I, JOHN COOPER, of Dublin, in the county of Wayne, and State of Indiana, have invented certain new and useful Improvements in Washing-Machines; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to washing-machines, and consists of an improvement in the manner of attaching the curved beaters to the central shaft, for which Letters Patent, No. 67,725, under date of August 13, 1867, were issued to me for a washing-machine. In the drawings—

Figure 1 is a view of a side elevation with one side of the box removed.

Figure 2 is a view of a vertical section on the line *y y* of fig. 1; and

Figure 3 is a view of a vertical section on the line *y' y'* of fig. 1, with the position of the beaters changed.

In the model accompanying my application for a washing-machine, for which Letters Patent, No. 67,725, were granted me, August 13, 1867, the beaters *E* were rigidly attached to the shaft *D*, and it was necessary to give the shaft *D* a rocking motion, so as not to carry the articles being washed over with them.

In constructing my improved washing-machine, I construct my box or tub as before, and mount therein the shaft *D*, providing it with a bearing at one end to receive the pin *A* upon which it turns, and at the other end with an oblong socket, *a*, as shown in figs. 2 and 3, for receiving the shaft *B*, by which it is turned, as shown in fig. 1. Before mounting the shaft *D* within the box *C*, I make two strips, *H*, of wood or other suitable material, and attach to them rigidly a series of bows, *E*, shaped as shown in figs. 2 and 3, and hinge them by hinges *F* to it, as shown in all the figures. The shaft *D* may be turned by a crank or by gear-wheels, when very rapid motion is desired.

In operating my improved machine the motion of the beaters creates a current on the surface of the water which, with the beaters, carries the upper surface of the clothing across to the other side of the box, and the striking of the current against the side of the box creates a current which descends the side and follows the round bottom of the box and comes up on the same side from which it started. This lower current coming in contact with the lower surface of the clothing, carries it to the other side. This motion of the current is constantly carrying the upper surface in one direction, while the under surface is carried in the opposite direction. The clothing or articles being washed are thus kept constantly revolving, without being carried over by the beaters or rolled into a wad.

It will readily be seen that the advantages of having the beaters thus hinged are that they will adjust themselves to the quantity of clothing in the box, whether it be large or small; that they will not carry the articles being washed over with them, and that when the shaft is turned in the opposite direction the hinged joints will be stiff, and the beaters will have all the advantages of a rigid attachment.

Having thus described my invention, what I claim is—

The shaft *D*, having the beaters *E* hinged to it as described, when constructed and arranged to operate substantially as set forth.

JOHN COOPER.
